Patented Apr. 4, 1922.

UNITED STATES PATENT OFFICE.

ZACH D. TALLMAN, OF OAKLAND, CALIFORNIA.

COLLAPSIBLE KNOCKDOWN CAMP STOVE.

1,411,596.

Specification of Letters Patent. Patented Apr. 4, 1922.

Application filed June 15, 1920. Serial No. 389,205.

To all whom it may concern:

Be it known that I, ZACH D. TALLMAN, a citizen of the United States, and resident of the city of Oakland, county of Alameda, 5 and State of California, have invented a new and useful Improvement in Collapsible Knockdown Camp Stoves, of which the following is a specification.

This invention relates to stoves and more 10 particularly to camp stoves of the portable character.

It is an object of the present invention to provide an improved camp stove consisting of a plurality of elements that are of extremely simple construction and of light 15 weight and which can be packed in very compact relation when the stove is knocked down.

A further object of the invention is to 20 provide, in a knock-down, collapsible stove, as few different elements as is practicable and to provide as many duplicate and interchangeable elements as possible for the facile securing of the parts in assembled stove- 25 forming position and, in this connection, it is a further object to provide elements that are not only duplicate and, therefore, interchangeable, but are also reversible in their several relations and positions; therefore 30 lending greatly toward the rapidity, ease, and convenience with which the elements may be assembled to form the stove and also enabling renewal and replacement by the simple ordering of a worn or lost element 35 that can be readily utilized in either of two possible positions and in which positions the said elements may be reversed.

A further object of the invention is to provide a collapsible knock-down stove structure in which the elements are constructed 40 and arranged with permanent or rigid respective means on each to interlock with complementary means on other elements without the requirement of any loose, and 45 therefore loseable and extraneous parts.

It is another object of the invention to provide details of arrangement and construction such that will insure the proper assembly of the stove elements in only one 50 and the correct position and which will be substantially fool proof in construction and that can be assembled without the exercise of expert knowledge and without the requirement of any tools.

55 A further object is to provide a stove structure having a plane unobstructed top,

thus giving maximum capacity for holding utensils or other objects placed thereon.

The invention possesses other objects and features of advantage, some of which, with the foregoing, will be made manifest in the following description of the preferred form of the invention which is illustrated in the drawings accompanying and forming part of the specification. It is to be understood that it is not intended to limit the invention to the embodiment shown by the said drawings and description as variations may be adopted within the scope of the invention as set forth in the claims. 70

Referring to said drawings:

Figure 1 is a perspective of the assembled stove with a part of the smoke stack broken away and also having a part of the cover broken away to show the interior of the 75 re-enforcing means.

Figure 2 is a central longitudinal vertical section through the stove.

Figure 3 is a section on line 3—3 illustrating the interlocking structure in substantially full size with the parts broken away and contracted for the purpose of conserving space in the drawing. 80

Figure 4 is a perspective of the lower portion of the assembled smoke stack and with 85 the bottom plate thereof in position to be attached to the lower end of the stack.

Figure 5 is a detail sectional view on a slightly larger scale than Fig. 2, illustrating more clearly the position of the parts at 90 the back upper portion of the stove and at the bottom of the stack.

Figure 6 is a sectional detail on a horizontal plane through the front corner of the stove at about a line indicated at 6—6 95 on Fig. 1.

Figure 7 is a perspective of a corner of one of the elements of the stove.

Figure 8 is a perspective of a corner of another element of the stove. 100

Figure 9 is a perspective of a form of reinforcing element for the top of the stove.

The invention is incorporated preferably in a type of stove having plane elements of sheet metal having the property of well 105 withstanding the effects of heat so as to provide a stove of durable construction and the form of stove as illustrated is substantially that of a rectangular or oblong box without a bottom as the stove may be erected immediately above or on a non-combustible surface, 110 such as earth or stone, as may be convenient.

The stove of the invention is provided with substantially duplicate longitudinal side members and with front and back members or elements of substantially equal area and similar in construction except that the front element is provided with a door for the admission of fuel and the rear element is provided with an outlet opening for circulation of air while a unitary top is included that is adapted to be applicable to and snugly fit upon the frame formed by the assembled and interconnected side to the back and front elements. Further, in order to promote combustion for the efficient burning of fuel in the stove, a collapsible stack structure is provided and is applicable to the back element of the stove and is designed to provide for the outlet of fumes of combustion through the outlet opening in the back. Further, the invention involves a stove, the elements of which are provided with rigid or permanent, and preferably integral, interlocking means, thereby eliminating the requirement of extraneous fastenings that not only may be lost but that are usually soon rendered either inoperative entirely or serviceable only with difficulty in the assembling of the parts.

In the form of the stove illustrated, substantially duplicate side elements 2 are made of sheet metal such as black iron, these sides being shown as oblong and plane, and may be of any proportion and weight of material. The end edges of the side elements or panels 2 are, as is clearly shown in Fig. 8, provided with inwardly turned flanges 2^a forming hooks to be interlocked with complementary means on the front element 3 and the back element 4 of the stove. As shown in detail in Figs. 6 and 7, the front member 3 and the back member 4 are respectively provided along their transverse edges with flanges 3^a and 4^a standing substantially perpendicular to the plane bodies of the front and back elements and the flanges 3^a and 4^a are themselves provided with inturned hook-forming portions 3^b and 4^b, these portions forming strips or flanges extending parallel to and spaced sufficiently from their respective flanges 3^a and 4^a to provide for the telescopic insertion of the hook-forming flanges 2^a on the ends of the respective side panels 2 in a manner clearly shown in Fig. 6. Thus, it will be seen that the framework of the stove will consist of the side panels 2 to the front ends of which are detachably interlocked by the telescopic flanges or hook-like means 2^a and 3^b, the front and rear elements 3—4. These interlocking means are, therefore, formed permanently and, in the case shown, rigidly with the front and side elements and, therefore, cannot be lost and will always operate to readily telescope one within the other by the endwise insertion of the one element or member on the other until the top edges of the frame-forming element, and

also the bottom edges, are brought into flush position or into a common plane. To facilitate the endwise insertion of the interlocking means, one within the other, the corners of the hook-forming means are preferably removed as, for instance, the corners of the hook-forming flanges 2^a of the side members 2 are beveled off inwardly as at 5 and, in the same manner, the flange 4^a and the hook-forming part 4^b of the back 4 are beveled off at 6 as is also the corresponding portions on the front 3, so that there will be no sharp corners to become bent over or to make difficult the insertion of the interlocking hook portions.

The front 3 is provided with a suitable door-way or opening 7 that may be covered by the door 8 hinged, or otherwise suitably connected, as at 9, to one side of the doorway 7 and the door may be secured in closed position by a simple latch 10, pivotally connected to the door 8 and adapted to be interengaged with a keeper 11 fixed on the outer face of the front 3. To provide for the admission of fresh air into the stove, suitable damper or inlet means is provided, in the present case including a damper 12 adjustably mounted over a damper opening 13 provided in the door 8.

The framework is rigidly secured in an upright and proper angular relation as between the front and side elements by the application to the top edges of the frame elements of a cover or top 14 formed preferably of sheet metal and shown as of oblong outline, the edges of the top having downturned flanges 15 to overhang the top edges of the sides and from the back and these top edges of these elements are preferably re-enforced by overturning and pressing down a re-enforcing, longitudinally extending flange portion 16.

To provide for the efficient combustion of fuel within the stove chamber, a smoke stack is provided and is constructed of a set of strips of suitable length, width, and weight of material, and the stack consists of front and back members 17 and 18 that are shown as provided along their longitudinal edges with inturned hook-forming flanges 19 similar to those above described on the front and back elements of the stove frame. These hook elements are adapted to telescopically interengage complementary hook flanges 20 outwardly turned on substantially duplicate side forming strips 21 of the smoke stack. The side strips 21 and the back strip 18 are of substantially equal length and each has at its lower transverse edge an out-turned flange 22 that is designed to be embraced by the complementary flange 23 provided on a bottom plate 24 adapted to be shifted by movement in the direction of the arrow, Fig. 4, on to the flanges 22 of the stack strips when they are assembled.

The front stack strip or section 17 is provided with a transverse outwardly turned flange 17^a on its lower edge that is adapted to rest upon the top 14 of the stove when 5 the stack is adjusted in position, as clearly shown in Figs. 1 and 2.

The lower portions of the side edges of the front stack section 17 are turned inwardly at 10 25, as indicated in dotted lines in Fig. 4, thus 10 interrupting the length of the interlocking hooks 20 somewhat above the bottom flanges 22. These inwardly turned flanges 25 are 15 designed to interlock with overturned hook-forming flanges 26, Fig. 5, formed on the vertical edges of an outlet opening 27 formed 20 in the upper portion of the back 4 through which opening may escape products of combustion from the stove chamber. The interlocking of the flanges 25 with the hook-forming flanges 26 serves to hold the stack 25 assembly in position securely upon the back 4 and the downward movement of the stack is limited in an assembly of the stove by reason of the engagement of the bottom 24 of 25 the stack with an outturned flange 28 at the bottom of the outlet opening 27.

From the above, it will be seen that the stack elements are interlocked to each other securely yet removably by means of the interengaging hook-forming flanges without the use of extraneous fastening means.

Since it is desirable to construct the top 14 of light but durable material and as it may be subjected to considerable weight 35 when utensils and the contents thereof are applied, the top is preferably re-enforced and this may be accomplished efficiently by the attachment to the under side thereof of braces or re-enforcing strips 30. Lightness 40 and yet rigidity of structure may be secured by forming these re-enforcing strips 30 in the shape of channel pieces having outer flanges 31 which in turn are inwardly and

upwardly folded, as at 32, thus providing double parallel and re-enforcing strips 45 which are further strengthened by the fold portion 33 connecting the flanges 31 and 32 of the respective sides.

The stove as thus constructed and built is capable of being readily knocked down and 50 all of the collapsed parts compactly assembled one upon the other to occupy a minimum space when the parts are to be packed away, either for storage or transportation, especially in cases when the stove is utilized 55 for automobile, camping and yachting purposes.

What is claimed is:

1. A knock-down camp stove having a box formed of sheet material elements including 60 sides, front and back pieces and a plane top, the back having a vent opening; and smoke-stack forming pieces adapted to be assembled and interlocked on the back and form a flue registering with the vent opening, leaving 65 the top unobstructed; the stack pieces having telescopic, hook-forming, longitudinal flanges, and a bottom closure attachable to the lower end of the stack and holding the stack rigid. 70

2. A knock-down camp stove having a box formed of sheet material elements including 75 sides, front and back pieces and a plane top, the back having a vent opening with side hooks and a bottom stop flange; and smoke-stack forming pieces adapted to be assembled and interlocked on the back hooks and form a flue registering with the vent opening, leaving the top unobstructed; and a bottom plate for the stack for defining the 80 position of the stack as it is applied on the stop flange.

In testimony whereof, I have hereunto set my hand.

ZACH D. TALLMAN.
